UNITED STATES PATENT OFFICE.

WILLIAM RAYMOND KINNEAR, OF NEW CASTLE, PENNSYLVANIA.

SHEET-SEPARATING MACHINE.

1,090,722.

Specification of Letters Patent. Patented Mar. 17, 1914.

Application filed September 17, 1909. Serial No. 518,196.

To all whom it may concern:

Be it known that I, WILLIAM R. KINNEAR, a citizen of the United States, and a resident of New Castle, in the county of Lawrence and State of Pennsylvania, have invented certain new and useful Improvements in Sheet-Separating Machines, of which the following is a specification.

The present invention relates to machines of that type employed for separating metallic sheets one by one from a stack or multiple layer after they have been annealed, and has for its purpose to provide a machine of that character which is portable in the sense that it may be transported to and mounted upon a stack of sheets which are to be separated, and which in its working is held in operative position progressively as the work is performed.

The machine is designed with a view of successfully replacing hand labor even with sheets adhering together in consequence of being rolled in groups or "frozen," such manual means as now employed being to loosen the sheets of the groups by kicking and then tearing off the sheets thus loosened with the aid of tongs.

The underlying principle of the machine resides in the use of a pair of knives or stripping blades which are caused to move in beneath the top sheet of a pile and completely separate the same therefrom, following which both knives simultaneously recede and one of them, provided with means for the purpose, carries the separated sheet with it to a conveyer mechanism when it is removed and forwarded for its further treatment. In order to insure the positive entrance of the knives a pneumatic suction apparatus is employed which raises diametrically opposite corners of the sheets adjacent to the edges at which the knives enter, said mechanism being timed to operate immediately in advance of the inward movement of said knives. And as a further assurance toward separation, a pressure device is provided which rests upon an intermediate portion of the pile, when the suction device is in operation, thereby utilizing the stiffness of the sheets to hold the second sheet from the top while the top sheet is being flexed at the corners.

The machine is supported in its entirety upon four screw threaded shafts and has means whereby these shafts may be intermittently rotated through the movements of

the separating knives and effect to move the machine downwardly as the sheets are being separated, and thus maintaining the machine in its operative position at all times, regardless of the height of the stack of sheets which are being worked. Coöperating with this latter mechanism is a means which contacts with opposed sides of the stack immediately following each operative movement of the separators, and by such contacting with the pile of sheets manages to keep the stack in proper symmetry during the separation thereof.

With the above objects in view, the invention is shown in its preferred embodiment, and in an alternative structure, in the accompanying drawings, wherein,

Figure 1 is a side elevation of the apparatus complete, Fig. 2 is a top plan view thereof, Fig. 2^a is a detail view of one of the separating blades, Fig. 3 is a view of part of the machine showing the same in elevation and partly in section, Fig. 3^a is a top plan view of one of the blade carriers and its operative mechanism, Fig. 4 is a detail view of the machine feeding mechanism, Fig. 4^a is a side elevation of the suction lifting mechanism, Fig. 5 is a further detail view of the parts shown in Fig. 3, Fig. 5^a is a side elevation of the depressing bar and its associated parts, Fig. 6 is a detail view of the compressor plate, Fig. 6^a is a side elevation of the compressor plate and its operating mechanism, Fig. 6^b is a detail view in side elevation of the clamping plate and its operating mechanism, Fig. 7 is an enlarged detail view of the mounting of one of the separator plates, Fig. 7^a is a side elevation showing the mounting of the separator plate supporting frame, Fig. 7^b is a detailed view of the sheet removing arms. Fig. 8 is a top plan view of an alternative construction of the machine. Fig. 9 is a side elevation thereof, Fig. 10 is a front elevation of the same partly in section, and, Figs. 11 and 12 are a top plan view and a side elevation of the operating mechanism.

Referring now to the details of structure of the machine, and with like characters of reference indicating corresponding parts in the several views shown, 1 designates the machine supporting means which comprises four vertically disposed screw threaded shafts suitably mounted to rotate in the base of bearing blocks 2, and at their upper ends connected by a skeleton frame 2'.

The machine frame 3 is in screw threaded connection with the shafts 1 through the medium of four integrally formed nuts 4 (see Fig. 1). At their upper ends each of the several shafts 1 is provided with a sprocket wheel 5 which is fixed thereon; and one of said shafts is additionally provided with a loosely mounted gear wheel 6 adapted to be coupled with said shaft through the medium of a clutch 7 that is splined thereon, and which coupling is effected through the medium of a controlling lever 8 journaled in the frame 2' at 9.

The means for rotating the several shafts 15 comprises an electric motor 10 supported upon a shelf 11 on the frame, and which motor normally drives a shaft 12 which, through the medium of a clutch 13, rotates a worm 14 that is normally in mesh with the worm wheel 6 and which transmits movement thereto as will be obvious, (see Figs. 1, 2 and 4.) For rotating the several shafts 1 in unison their sprocket wheels 5 are connected by a chain 15. Any slack in 25 the chain is compensated for by the take-up 15'; and said chain and sprockets 5 are held against freedom of movement by the friction brake, 16'. The motor 10 is designed to be constantly operated, and in order to transmit its power to cause the rotation of the shafts 1, and control the consequent downward movement of the frame 3, which occurs through gravity, there is provided an automatic means operable intermittently and 30 through the reciprocating movement of one of the sheet separating knives. This means comprises an arm 16 fixed at one end to a stub shaft 17 and at its opposite end connected with one element of the clutch 13. 35 The shaft 17 is journaled in a bearing 18 and at its lower end has a fixed short arm 19 that in turn connects with a bar 20. The bar 20 is pivotally connected to an arm 21 that is fixed on a shaft 22 within a journal bearing 23 that is mounted on the frame 2'. The shaft 22 has a second arm 24 which is also fixedly mounted thereon, and which projects inwardly of the machine as shown in Fig. 2, and in which position it lies normally in the path of a double faced cam 45 block 25, which block is mounted upon and reciprocates with one of the sheet separating knife carriers. It will be seen from the foregoing that as the separating knife is reciprocated the cam faces of the block 25 will alternately engage with and elevate the projecting lever 24, which movement through the several members described will cause said upward movements of the arm 24 to 50 couple and uncouple the clutch 13, thereby transmitting power from the motor to the several shafts 1, and causing the rotation of the latter for brief periods, *i. e.*, the rotation of these shafts will be sufficient to cause 55 the downward movement of the machine a

distance sufficient to compensate for the thickness of the sheet which has been removed, and properly position the separating knives for the next operation.

The means for actually separating the sheets of the pile A comprises a pair of laterally and oppositely reciprocating plates or blades 26 and 27 which are mounted in carriages 26' (one being shown in Fig. 7) that slide within guideways 28 formed in the sides of the machine frame 3, (see Figs. 1, 2 and 3a). The separating blades are preferably pivotally mounted (see Figs. 7 and 7a) in their respective carriages, to effect which they are secured on the ledges 28' of said carriages by means of screws 29' and the supporting rails 28' are in turn pivotally mounted as at 32', and to hold the blades in proper symmetry, and also permit them to compensate for any irregularity in the strata of the sheets of the pile, they are held tensioned by leaf springs 30', which springs are adjustably secured to the plate carriages by bolts 31'. Each of the plate supporting rails has a downwardly projecting portion such as 33' adapted to coöperate with a similar member 34' on a fixed bar 35', the purpose whereof will be presently explained. For reciprocating said plates there is provided a motor 29 mounted upon a platform 30 on the frame 3. The shaft 31 of this motor is provided with a pinion 32 which, through a train gearing 33, 34, 35 and 36, operates a pair of crank arms 37. The crank arms 37 carry links 38 which connect with stub shafts 39 carried by the knife carriage 40, and which project through their respective guideways 28, (see Fig. 1.) A pair of stub shafts 39 carries rack bars 41 which mesh with pinions 42 that are loosely mounted on the shaft 43 which carries the pinion 36. The loosely rotating pinions 42 have also meshing therewith similar rack bars 44 which are carried by the guiding members 45 of the opposite blade carrying carriage 26', and which travel in the ways 28. For normally keeping the rack bars 41 and 44 always in mesh with the pinion 42, said rack bars are engaged and held in that relation by spools 46, as shown in Fig. 1.

From the description just given, it will be readily seen that the power of the motor transmitted through the train gearing 32-36 will, through the links 38, reciprocate the sheet separating blade 27, and that the movements of this blade will through the gearing 41, 42 and 44, cause its coöperating blade 26 to be operated simultaneously therewith and in the opposite direction.

It is devised that the topmost sheet of the pile A be gotten into position for receiving the blades 26 and 27 which effect its separation from said pile, and to accomplish this

a pneumatic suction apparatus is utilized. This apparatus comprises a pump 47 (see Figs. 3, 9 and 10), whose piston is operated through a pitman 48 that is eccentrically mounted on the shaft 49. Extending from the pump 47 are two flexible pipes 50 which lead to diametrically opposite corners of the stack of sheets A where they are connected with plungers 51. The plungers 51 are adapted to have slight vertical movement in sleeves 52 which support said plungers from the cross bar 53 of the machine frame to which they are connected by the arms 54. The means for giving movement to the plungers 51 comprises a pair of oppositely disposed lifting bars 55 which are pivotally mounted on upwardly disposed arms 56 that are in turn secured upon the cross bar 53. The free ends of the lifting bars 55 are adapted to move within guideways 57 of the plungers 51, and intermediate of their pivots and free ends said bars span the shaft 49, and at these points said shaft 49 carries cams 58 whose function is to give to the bars 55, and consequently the plungers 51, their slight upward and downward movement, as above stated. Each of the sleeves 52 is provided with a presser foot 52' loosely mounted therein and whose upper end fits freely through a plate 53' carried by the plunger, where it is bent and rests upon said plate and by reason of which, and having the spring 54' tending to normally depress the same, said presser foot holds down that corner of the sheet immediately adjacent that portion where the suction nozzle 59 grips it. The hold down members 52' are so mounted that they continue for a brief period to depress the corners of the sheet while the plungers are lifting and thus prevent the second sheet being also lifted. On the final upward movement of the plungers, the presser feet are also lifted clear of the pile. The suction apparatus just described is timed so that the nozzles 59 on the plungers 51 are brought into contact with the topmost sheet of the pile immediately after the sheet just separated therefrom has been removed clear of the pile, and simultaneously with this contacting of the nozzles 59, suction is created by the pump 47, and instantly this suction is created the plungers 51 are moved upwardly through the medium of the cams 58 and the lifting arms 55. Each of the nozzles 59 is connected with its respective plunger or tube 51 by a pivot pin 60 and a loose connection 61 disposed in such manner that in the upward movement of said plungers 51, the nozzles 59 assume an angular position and by doing so cause the extreme corners of the sheet to be lifted prior to the adjacent portion thereof. The reason for this provision is to have the topmost sheet of the pile instantly prepared to receive the advanced edges of the separating plates 26 and 27. As the corners of the sheets are flexed in the manner stated, their respective intermediate corners are at the same instant held in close contact with the pile by means of depressing fingers 59' mounted to have slight vertical movement in arms 60' that are supported by the cross bar 53 (see Figs. 3 and 5^a). Said depressing members 59' are connected at their upper ends with levers 61' which are in turn pivotally supported on the machine frame at 62', and as in the instance of the lifting arms 55, the arms 61' are adapted to be elevated and depressed alternately therewith by cams 63' that are carried by the shaft 49. As the separating blades are advanced toward the pile, the projecting members 33' engage with the members 34' on the fixed bar 35' and thereby cause the blades to be lifted slightly as they enter beneath the topmost sheet of the pile, and thus overcome the likelihood of the blades engaging under the second sheet should the same for any reason incline to be lifted upward with the sheet to be separated. The time for this lifting of the blades 26 and 27 is so selected that immediately after the blades have entered beneath said top sheet, they will drop to the level of the top of the pile.

Cooperating with the suction apparatus is a means for depressing or holding down the central portion of the sheet being separated in order to insure the separation of only that sheet and also to maintain the proper symmetry of the pile. This means comprises a flexible presser plate 62 that is dependably supported from a cross head 63. The plate 62 is suspended from the shaft 49 by bangers 65, and for bringing said plate into contact with the pile the cross head 63 is provided with a shaft 66 that is hung from an eccentric bearing 67 also mounted on the shaft 49. The flexible plate 62 comprises four sections 62' which are coupled together by hinge joints 68 in such manner as will give them independent or separate movement relative to each other. The depressing plate has its operative mechanism so timed that it is depressed during the lifting of the corners of the sheet by the suction apparatus but will itself be lifted clear of the pile at the proper movement or at that instant when the separating knives 26 and 27 complete their inward movement.

As each sheet is separated after the manner described it is removed from the pile by a pair of fingers 69 that are carried by the blade 27. The free ends 70 of said fingers are hooked (see Fig. 7^b) so as to readily engage the rear edge of the sheet separated and withdraw the same with said blade 27 on its return movement. When the separated sheet has been thus removed from the pile, it is brought into frictional engagement with a pair of rollers 71 that are 130

mounted on a shaft 72. The shaft 72 is journaled in a pair of blocks 72' which have vertical movement in a pair of guideways 73' upon the frame 3, the friction disks 71 are normally kept in position to engage the sheet to be removed through the medium of the springs 74'. The shaft 72 carrying the friction rollers is given rotary movement by a chain 73 that is driven by the shaft 49. The stripping rollers 71 thus cause the separated sheet to be removed from the machine on to a suitable carrier or otherwise.

It is desired to keep the stack of sheets A in proper symmetry whereby the machine may work thereon, after once set, without necessitating any subsequent positioning or adjustment of the apparatus or stack of sheets. To this end, the machine is provided with a means that centers or positions the topmost portion of the stack progressively as the frame 3 is lowered with the stack. This mechanism comprises a pair of presser plates 74 that are disposed on opposite sides of the stack, as shown in Figs. 1, 2, 8 and 9. These plates 74 are designed to come into contact with the pile A between those operations of the machine which remove the sheets. To effect this operation each of the plates 74 is carried by a head 74' that is movably supported on the bearing 75, and through links 76 is connected to the machine frame at 77. Each of the blade carriers is provided with a grooved track member 78 that travels with said carriers and on each movement thereof causes the links 76 to be straightened or broken for bringing the blades 74 into engagement with the pile and removing the same therefrom.

Referring now to the alternative structure shown in Figs. 9 to 12, the same comprises a frame 79 which supports the sheet separating apparatus in its entirety and is in turn supported by and lowered progressively with the stack of sheets as separated. The means for causing the reciprocations of the knife carrying carriages and the structure thereof is substantially the same as in the machine above described, and need not therefore be entered into in further detail here. It differs, however, in that the motor for actuating the same is not mounted upon the machine frame. This feature of the machine will be described hereinafter. The suction apparatus for flexing the sheets in the present instance comprises vertically movable plungers 51 having nozzles of the type above described and having their movement within sleeves 80 that are supported by arms 81, which arms are in turn supported upon the machine frame by a pair of inwardly disposed bars 82 mounted on the frame extensions 83, as shown in Figs. 8 and 9. The lifting arms for the plunger 51 are structurally the same as the corresponding

members in the other instance, and are operated in precisely the same manner. The pump 47 is also in structure and manner of operation similar to that shown and described in the preceding figures. The presser plates 74 for maintaining the pile in proper symmetry are likewise the same, and are operated during the reciprocations of the blade carrying carriages. In the preferred type of machine, however, the plate 84 is rigid as distinct from being flexible like the plates 62, and constitutes the means for supporting the machine upon the stack of sheets during their separation. The plate 84 is dependingly supported by a cross head 85 and is adapted to have slight vertical movement through the rotation of the shaft 49, to effect which it is connected therewith by an eccentrically mounted hanger 86. On each upward movement of the supporting plate 84 the side presser plates 74 are designed to contact with the pile and support the machine, and co-operating with said presser plates is a pair of plates 87 disposed on opposite sides of the stack A. Said plates 87 are formed rigidly with the machine and normally lie slightly in contact with the sides of the pile A. In this type of machine, the pair of friction rollers 71 are mounted on the machine by the two arms 88 in such manner that said rollers may rest by their own weight upon the upper surface of one of the sheet separators. Movement is imparted to the friction roller 71 through the medium of a chain and sprocket gearing 89 from the shaft 49, as shown in Fig. 8. The motor 90 which operates the machine is carried upon a truck 91 and is in gear with the sprocket 92 of the machine by a chain 93. The truck 91 is held at the proper distance from the machine by a pair of reach arms 94, which arms are further serviceable in that as the machine frame 79 is lowered, the truck 91 is moved away from the stack, which enables said frame to clear the motor 90 to lower the truck 91.

Having thus described my invention, what I claim as new therein and desire to secure by Letters Patent, is:

1. A sheet separating machine adapted to be supported upon the sheets to be separated and be lowered therewith progressively as the sheets are separated, and means for temporarily supporting the frame upon the sheets during the separation of said sheets.

2. A sheet separating machine adapted to be supported upon a pile of sheets to be separated and be lowered therewith progressively as the sheets are removed, and means adapted to engage the sides of the pile on the actual separation of each sheet and support the machine.

3. In a sheet separating machine, the combination with a suitably supported frame,

of a suction device, a stripping means co-operating therewith and adapted to engage beneath and completely separate a sheet from a pile, and means carried by the stripping mechanism for removing the sheet separated.

4. In a sheet separating machine, the combination with a suitably supported frame, of suction means for raising the corners of the sheets in advance of their separation, a reciprocating knife adapted to engage under said raised portions and completely separate the sheets from the pile, and means carried with the knife for removing the separated 15 sheets.

5. In a sheet separating machine, the combination with a suitably supported frame, of suction means for raising the corners of the sheets in advance of their separation, a 20 pair of oppositely and simultaneously operated knives adapted to engage under said raised corners and completely separate the sheets from the pile, and means carried with one of said knives for removing said sheets.

25 6. In a sheet separating machine, the combination with a suitably supported frame, of suction means for raising opposite corners of the sheets in advance of their separation, a pair of oppositely and simultaneously operated knives adapted to engage under said raised corners and completely separate the sheets from the pile, means carried by one of said knives for withdrawing the sheets when separated, and means for removing the 30 sheets withdrawn.

7. In a sheet separating machine, the combination with a frame adapted to be supported upon the sheets to be separated, and means for temporarily supporting the machine during the actual separation and removal of each sheet, said supporting means adapted to keep the sheets in proper stack formation.

40 8. In a sheet separating machine, the combination with a portable frame having means adapted to support the same upon a stack of sheets to be separated, of a suction means adapted to raise the corners of the sheets, stripping mechanism co-operating therewith and adapted to separate the sheets, clamps adapted to engage opposite sides of the stack and support the frame on the separation of each sheet, means for withholding said first supporting means while said 45 clamps are effective, and means for withdrawing and removing the sheets as separated.

9. In a sheet separating machine, the combination with a portable frame having means 50 to support the same upon a stack of sheets to be separated, of a suction means adapted to successively raise opposite corners of the top-most sheets of the stack, stripping mechanism co-operating therewith comprising a

pair of oppositely and simultaneously actuated knives adapted to engage under the raised corners of the sheets and separate the same from the stack, means carried by said stripping mechanism for withdrawing the sheets as separated, clamps adapted to engage opposite sides of the stack and support the frame on the separation of each sheet, means for withholding said first supporting means while said clamps are effective, and means for removing the sheets withdrawn. 65

10. In a sheet separating machine, the combination with a suitably mounted frame, of a suction device therefor, said suction device comprising a tube having a nozzle hinged thereon and adapted to raise a corner 70 of the sheet while keeping the adjacent portion thereof depressed, stripping mechanism adapted to engage under the raised corner of the sheet and separate the same, and means for withdrawing and removing the 75 sheets separated.

11. A suction device for sheet separating machines comprising a tube, means for lifting said tube, a nozzle hinged on the lower end of the tube and adapted to raise one 80 portion of a sheet while depressing an adjacent portion thereto when the tube is lifted, and means for creating suction through the tube.

12. The combination in a sheet separating machine, of a means for positioning the sheets for separation, comprising a tube, means for lifting the tube, a nozzle mounted on the lower end of the tube and adapted to assume an angular position relative thereto 90 when the tube is elevated, whereby to raise one portion of a sheet and depress a portion adjacent thereto, and means for creating suction through the tube.

13. In a sheet separating machine, the combination with a suction device for raising a portion of the sheet, and a reciprocable separating knife adapted to extend beneath the sheet and the full width thereof, of means for depressing a portion of the sheet 100 being removed adjacent the raised portion thereof whereby to prevent the next adjacent sheet rising under the influence of the sheet being raised.

14. In a sheet separating machine, a suction device for raising a portion of the sheet and a reciprocable separating knife adapted to extend beneath the sheet and the full width thereof, and a presser foot co-operating with the suction device and adapted to 110 depress a portion of the sheet being removed adjacent to the suction device during the raising of said sheet, and through said depressed portion, holding back the next sheet 115 from the influence of the sheet being raised. 120

15. In a sheet separating machine, a suction device for raising a corner of the sheet to admit a reciprocable separating knife

extending across the sheet and a presser foot carried by the suction device and adapted to depress the portion of the sheet being removed adjacent the suction device during the raising of said suction device.

16. In a sheet separating machine, a suction device for raising a corner of the sheet and a reciprocable separating knife extending across the sheet and a spring pressed foot carried by the suction device and normally tending to depress the corner of the sheet adjacent the suction device.

17. In a sheet separating machine, the combination with a frame having means adapted to support the same upon a stack of sheets to be separated, of suction means adapted to raise a corner of a sheet, stripping mechanism coöperating therewith and adapted to separate the sheets, a presser foot for holding down a corner of the sheet opposite to the suction device, means for lifting the frame supporting means during the separation of each sheet, and means whereby the presser foot is caused to be depressed on the initial raising of the frame support.

18. In a sheet separating machine, the combination with a suitably supported frame, of an edge lifting device acting upon the top sheet for initial parting of the same

from the sheet beneath it and knife-like 30 wedging means lying in the plane of separation, movable in said plane of separation to forcibly lift the top sheet from the next sheet to which it adheres, and having a scope of movement, which completely raises the 35 sheet to be severed from the one to which it adheres.

19. In a sheet separating machine, the combination with a suitably supported frame, of an edge lifting device acting upon 40 the top sheet for initial parting of the same from the sheet beneath it and knife-like wedging means lying in the plane of separation, movable in said plane of separation to forcibly lift the top sheet from the next sheet to which it adheres, and having a scope of movement, which completely raises the sheet to be severed from the one to which it adheres, and a presser plate above the sheet to be separated, holding the same parallel to the plane of separation and thereby preventing buckling.

The foregoing specification signed this 8th day of September, 1909.
